UNITED STATES PATENT OFFICE.

EMRI W. CLARK, OF NASHUA, NEW HAMPSHIRE.

SNOW-GUARD.

SPECIFICATION forming part of Letters Patent No. 625,144, dated May 16, 1899.

Application filed December 24, 1898. Serial No. 700,196. (No model.)

To all whom it may concern:

Be it known that I, EMRI W. CLARK, a citizen of the United States, residing at Nashua, in the county of Hillsborough and State of 5 New Hampshire, have invented a new and useful Improvement in Snow-Guards, of which the following is a specification, reference being had to the accompanying drawings, in which—

10 Figure 1 is a top plan view of a part of a roof, showing my new snow-guard in place. Fig. 2 is a section on the line $\alpha\alpha$ of Fig. 1. Fig. 3 is a perspective view of my new snow-guard. Fig. 4 shows a modification in per- 15

The object of my invention is to provide a snow-guard which can be put in place on any shingled or slated roof, new or old, and of any pitch and with any length of the covering 20 exposed to the weather.

My invention consists in the snow-guard hereinafter described and claimed.

In the drawings illustrating the principle of my invention and the best mode now known 25 to me of applying that principle, A is the body portion, one end of which is bent to form a hook A'. The other end of the body portion A is notched by bending up a portion A² at right angles to the body portion A. To 30 the part A² is riveted a triangular-shaped brace B, from each side of which projects the triangular-shaped wings B' B'.

I do not wish to be understood as limiting myself to the particular construction, for the 35 snow-guard may be made in a single piece and the parts may be of a different shape, either cast or struck up, from that described without departing from the principle of my invention.

40 In the modification shown in Fig. 4 a second pair of wings D D project from the lower outer end of the triangular-shaped brace B'.

In fitting my snow-guard to new roofs the body portion A is secured in place by the 45 hook A' hooking over the upper end of the shingle E or slate, the vertical portion A being placed between the shingles or slates F F of the row next above. In fitting my snow-guard to old roofs the body portion A, 50 which is very thin, is inserted under the shingles (or slates) F F, over the shingle E, and

is pushed upward until the end of the hook A' is clear of the upper end of the shingle E, the vertical portion A² entering between the shingles F F. The snow-guard is then drawn 55 down, the hook A' hooking over the end of the shingle E, thereby securing the snow-guard in place.

The snow-guard possesses the following advantages:

First. It may be used on old or new roofs, shingles or slate, of any pitch and with any exposure to the weather.

Second. The sidewise-projecting wings bear 60 at their lower edges on the shingles between 65 which the vertical portion A² lies. These wings prevent "cocking" or twisting of the snow-guard about its longitudinal axis, and thereby keep the guard in an operative position.

Third. The piece B acts as a brace to stiffen 70 the construction as well as to act as a point of support for the wings.

Fourth. The flat body portion has a more 75 extended bearing than any snow-guard known to me. This extended bearing distributes the pressure of the snow and ice over a larger area, and thereby avoids the cracking of the slate upon which the guard rests. Moreover, the thinness of this flat body por- 80

tion permits its easy and ready insertion under slates already laid, as in old roofs, as well as under slates which are being newly laid, as in new roofs. An especial advantage lies 85 in the entire absence of strain when the body portion is inserted underneath it, and this absence of strain is due to the thinness and flatness of the body portion. In the forms heretofore used the thickness of the body portion greatly strained the slate and the width 90 of the slate afforded much leverage. The result was that the plate was fractured by the insertion of the thick body portion, or, if not fractured then, it was placed under such a strain that the addition of a slight strain, as 95 that produced by a weight of snow and ice, resulted in its immediate fracture. The thin body portion is therefore a most important feature of my invention.

The wings D D (shown in the modification, 100 Fig. 4) give the brace B² a bearing on the shingles F F, and thereby hold the shingles

FF down against the upward pressure of the body portion A.

What I claim is—

As a new article of manufacture, a snow-
5 guard made up of a body portion provided at one end with a downwardly-turned hook and at the other end with an upwardly-turned lengthwise-extending brace; said brace being provided with sidewise-projecting wings.

In testimony whereof I have signed this 10 specification, in the presence of two subscribing witnesses, on this 22d day of December, A. D. 1898.

EMRI W. CLARK.
